CANOPY

William R. Orr, 4907 Ohio Garden Road,
Fort Worth, Tex.

Filed Jan. 18, 1960, Ser. No. 59,088

Term of patent 14 years

(Cl. D13—1)

The dominant features of my design reside in the portions shown in full lines.

I claim:

The ornamental design for a canopy, substantially as shown and described.
